CRAWLER MOUNTED LOOP MINER

Joseph F. Joy, Fort Pierce, Fla., assignor to Joy Manufacturing Company, Pittsburgh, Pa., a corporation of Pennsylvania

Filed June 1, 1956, Ser. No. 588,786

8 Claims. (Cl. 262—9)

This invention relates to mining machines and more particularly to a crawler mounted loop miner especially designed for mining coal or other minerals in underground mines.

The machine of the present invention constitutes an improvement over those disclosed in my copending applications Serial No. 214,242, filed March 7, 1951, now Patent No. 2,730,346 and Serial No. 296,325, filed June 30, 1952, now Patent No. 2,796,246 and is especially designed for use in accordance with the method of mining disclosed in my copending application Serial No. 296,323, filed June 30, 1952 now abandoned; all of these applications being owned by a common assignee.

An object of this invention is to provide an improved mining machine. Another object is to provide an improved mining machine of the type known as a loop cutter having improved cutting mechanism. Still another object is to provide an improved core cutting and core breaking means for a mining machine. A further object is to provide an improved reversible loop cutter which may operate in substantially right angled positions from either side of the machine thereby to enable operation of the machine in either of opposite directions along a mine vein. A still further object is to provide an improved combined cutting and conveying means for a mining machine and improved driving means for the cutting and conveying means. Still another object is to provide an improved mining machine having novel arrangements and combinations of parts. These and other objects and advantages of the invention will however more fully appear in the course of the ensuing description.

In the accompanying drawings there is shown for purposes of illustration one form which the invention may assume in practice.

In these drawings:

Figs. 1a, 1b and 1c, taken together, constitute a plan view of the improved mining machine.

Figs. 2a and 2b, taken together, constitute a side view of the mining machine shown in Figs. 1a, 1b and 1c.

Figs. 3a and 3b, taken together, constitute an end view of the mining machine, showing the combined loop cutter and conveyor and a portion of the drive therefor.

Fig. 4 is a cross section taken on line 4—4 of Fig. 1b.

Fig. 5 is a horizontal section taken in planes of line 5—5 of Fig. 3b, showing details of the loop cutter and conveyor.

Fig. 6 is a cross section taken on lines 6—6 of Figs. 1b and 1c.

Fig. 7 is a vertical section showing the cutter and conveyor taken on line 7—7 of Fig. 3a.

Fig. 8 is a horizontal section taken on line 8—8 of Fig. 3a.

Fig. 9 is a cross sectional view, on a reduced scale, taken on line 9—9 of Figs. 1b and 1c, and showing the mining machine in operating position in a mine.

Fig. 10 is a diagrammatic plan view of the mining machine shown in Fig. 9, showing the loop cutter and

2

conveyor in reversed positions as indicated in full and dotted lines.

The improved mining machine, as shown in the drawings, generally comprises a mobile base 1, desirably a tractor base, having a frame 2 on which is pivotally mounted on a horizontal transverse axis at 3 a tiltable frame 4 which overlies the base frame and extends longitudinally forwardly and rearwardly beyond the ends of the base. Carried at the rearward portion of the tiltable frame 4 at the rear end of the machine is a horizontal, laterally projecting, reversible, combined loop core cutter and conveyor generally designated 5 and associated with the cutter and conveyor is a core breaking means 6. Conveying means 7 extends longitudinally of the tiltable frame 4 for receiving the mineral dislodged from the mine vein by the core cutting and breaking means and for moving the dislodged mineral longitudinally in a forward direction to discharge onto an extensible conveyor 8.

Arranged at opposite sides of the rearward portion of the tiltable frame 4 are extensible power jacks 10 desirably fluid jacks having upright fluid cylinders 11 containing pistons 12 having downwardly extending piston rods 13 engaging the top surfaces of horizontal abutment plates 14 on the base frame. The tiltable frame 4 has lateral horizontal plate portions 15 provided with openings 16 through which the piston rods extend, as shown in Fig. 4.

The mobile tractor base 1 comprises side tread frames 17 about which endless crawler treads 18 are guided for orbital circulation and the crawler treads may be driven in any conventional manner to effect propulsion and steering of the machine.

The reversible core cutting and conveying means 5 comprises a swivelled support or hanger frame 20 (Fig. 6) having aligned vertical shaft portions 21 and 22 journaled in bearings respectively supported by an upper plate 23 and a bottom bearing support 24. These upper plate and bottom bearing supports are carried by the rearward portion of the tiltable frame 4 as shown. The swivelled hanger support 20 carries a generally rectangular shaped cutter and conveyor frame or open-centered loop cutter bar 25 having guideways 26 at the front and rearward sides thereof in which parallel endless cutting and conveyor chains 27 and 28 are respectively guided. This cutting and conveying frame and the endless chains guided thereon and the associated core breaker means 6 may be generally similar to those disclosed in my copending application Serial No. 194,259, filed November 6, 1950, now Patent No. 2,910,283, also owned by the assignee of the above mentioned copending applications.

The loop shape or open-centered rectangular cutter and conveyor frame 25 includes a generally U-shaped lower frame portion 29 and an inverted generally U-shaped upper frame portion 30 and the latter portion has depending vertical guide portions 31 and 32 received in vertical guideways of upstanding portions 33 of the lower frame 29. The frame portions 33 carry extensible power jacks 34 desirably of the fluid type comprising vertical fluid cylinders 35 containing pistons 36 having upwardly extending piston rods 37 secured at 38 to the upper frame portion 30 as shown in Fig. 6. Thus when fluid under pressure is properly supplied to the jack cylinders 35 the pistons 36 may be moved upwardly to elevate the upper frame portion 30 relative to the lower frame portion 29 and by trapping fluid in the cylinders the parts may be firmly locked in adjusted position. Any conventional control valve means may be provided for controlling the flow of pressure fluid to and the venting of fluid from the jack cylinders.

The parallel cutting and conveying chains 27 and 28

have laterally projecting chain links 40 which support conventional cutter bits 41 and the rows of cutter bits project in opposite directions from opposite sides of the cutter and conveyor frame as shown and the forward chain acts as a cutter chain while the rearward chain acts as a conveyor chain, as disclosed in my copending application Serial No. 214,242 above referred to. There is sufficient slack in the loosely hanging or looped cutting and conveying chains so that when the loop frame is in its lowered collapsed position (Fig. 3b) adjustment in elevation of the loop frame is permitted, as above described, and it is also common practice to provide some sort of automatic take-up for the slack in the chains when desired. The swivelled support 20 for the loop bar may be swung about its pivot to locate the cutting and conveying chains and the core breaker means in operating positions at either side of the machine, in a manner to be later described in detail.

The means for swinging the cutter frame horizontally about its pivot may assume various forms but herein, for illustrative purposes, comprises oppositely acting extensible power jacks 42 and 43 desirably of the fluid type comprising parallel reciprocable fluid cylinders 44 arranged closely side by side and containing pistons 45 having oppositely extending piston rods 46 secured at 47 to the frame 4. Carried by these reciprocable cylinders are guide sheaves 48 and 49. A cable 50 is attached at its ends at 51 within a circular member or disk 52, and is formed integral with the upper shaft 21 of the swivel hanger frame 20 and the opposite strands of this cable extend from the opposite sides of the circular member 52, around the sheaves 48 and 49, and is secured at 53 at its intermediate portion to the frame. Thus when fluid under pressure is properly supplied to the jack cylinders one strand of the cable may be drawn in while the other is payed out to effect turning of the circular member 52 together with the swiveled hanger frame 20 about its pivot thereby to swing the loop cutting and conveying chains and the associated core breaker means from one side of the machine to the other. When fluid is trapped in these swing cylinders the parts may be firmly held in adjusted position. Any suitable control valve means may be provided for controlling the flow of pressure fluid to and the venting of fluid from the swing cylinders.

The driving means for the loop cutting and conveying chains 27 and 28 may also assume various forms but herein, for illustrative purposes, comprises a pair of motors 55 (Figs. 1b and 5) carried by the tiltable frame 4 and operating in unison, the motors having parallel shafts 56 (see also Fig. 4) extending longitudinally of the machine. Secured to the parallel motor shafts are spur gears 57 meshing with and driving a central spur gear 58. Splined at 59 to the hub of the spur gear 58 is a coaxial shaft 60 which is in turn connected as by a key 61 to an aligned shaft 62 suitably journaled in a gear housing 63 carried by the tiltable frame 4. The shaft 60 is directly connected by a conventional sliding clutch 64 to a chain sprocket 65 which engages and drives the cutter chain 27. The shaft 60 is shiftable axially by a power device 66 which includes a fluid cylinder 67 containing a reciprocable piston 68 having its piston rod 69 rotatably connected to the shaft. Thus when fluid under pressure is properly supplied to the cylinder the shaft may be moved axially selectively in either of opposite directions. Any suitable control valve means may be provided for controlling flow of fluid to and venting of fluid from the cylinder. Keyed at 70 to and driven by the shaft 62 is a spur gear 71 meshing with a larger spur gear 72 suitably journaled on a shaft 73 supported within the gear housing. Secured to the gear 72 is a small spur gear 74 meshing with a relatively large spur gear 75 rigidly secured as by screws 76 to the hub of a chain sprocket 77 suitably journaled on the shaft 62.

The chain sprocket 77 engages and drives the rearward endless conveyor chain 28. It will thus be seen that the motors, through the gearing above described, effect drive of the cutter chain 27 at a relatively high cutting speed and effect drive of the conveyor chain 28 at a relatively low conveying speed. The chain sprocket 65 is journaled on the shaft 62 and has its hub secured as by screws 78 to a relatively large spur gear 79 meshing with a small spur gear 80 likewise suitably journaled on the shaft 73. Rotatable with the gear 80 is a relatively large spur gear 82 identical in size to the spur gear 72. During drive of the chain sprocket 65 at a relatively high speed the gears 79, 80 and 82 merely idly rotate.

When the cutting and conveying bar is swung into a right angle position at the opposite side of the machine as indicated in dotted lines in Fig. 10 the sprocket 77 is directly clutched to the shaft 60 for drive at a relatively high speed and at that time the then forwardly located chain 28 serves as the cutter chain and the high speed sprocket 65 is driven at a relatively low speed through the gearings 71, 82, 80 and 79 for driving the then rearwardly located chain 27 which then acts as a conveyor chain at a relatively low speed. The manner of transposing the parts to effect reverse drive of the chains will later be described.

A detachable pin 81 is receivable in registering holes 81' on the swingable frame 20 and the lateral plate portions 15 for locking the loop cutter in either of its right angle positions about its pivot (Fig. 1b) at either side of the base.

Now referring to the core breaker means 6 it will be noted that supported by a transverse frame 83 rearwardly of the loop cutter and conveying bar is a series of parallel breaker wedges 84 arranged with their axes in a common horizontal plane and extending within the open center of the cutter and conveyor bar or loop frame. The transverse frame 83 is detachably secured as by screws 85 to end frames 86 carried by the swiveled hanger frame 20 mounted on the rearward portion of the tiltable frame 4. The breaker wedges 84 have spiral vanes 87 and carry forwardly located drill bits 88. These wedges have their tapered bodies threadedly attached at 89 to shafts 90 suitably journaled within the transverse frame 83. Keyed to the parallel shafts 91 are intermeshing spur gears 92 contained within the frame chamber 93 for driving the wedges in unison. Secured to an outer shaft 91 is a chain sprocket 94 connected by an endless drive chain 95 to a chain sprocket 96 having a sleeve-like hub 97 keyed at 98 to the rearward end portion of the shaft 62. Extending downwardly from the transverse frame is a transverse guard plate 99 for retaining the dislodged mineral in the path of the rearward conveyor chain as shown in Fig. 7, and a troughlike frame 100 extends transversely across the rearward portion of the frame 4 to provide a longitudinal continuation of the guard plate 99. This troughlike frame 100, as shown in Fig. 3b, is desirably secured as by screws 101 to a substantially semi-circular portion 102 (Fig. 1b) of a troughlike conveyor frame 103.

The conveyor 7 comprises an endless chain 104 carrying lateral flights 105 which travel along the troughlike passageway 106 provided by the frame 103. The rearward portion of the endless conveyor travels beneath the inner portions of the cutting and conveyor chains as shown in Fig. 6, and in the reversed positions of the cutter and conveyor bar the front cutter chain moves along troughlike frames 107 carried by the hanger frame 20 and projecting laterally from the sides of the conveyor frame. The rear conveyor chain travels in a troughlike passageway 108 provided by the detachable frame 100 in the reverse positions of the bar. Thus the rear conveyor chain conveys, in either reversed position of the bar, the dislodged mineral laterally to discharge onto the conveyor 7 and the dislodged mineral is conveyed forwardly lengthwise of the machine by the conveyor 7 to discharge onto the extensible conveyor 8 (Fig. 10).

When it is desired to swing the loop cutter and conveyor frame to the opposite side of the machine to effect reverse operation the transverse wedge carrying frame 83 may be detached from the machine frame, the drive chain 95 may be disconnected and the troughlike frame 100 may be removed thereby to permit swinging of the bar hanger frame 20 about its axis to locate the bar in a substantially right angle position at the opposite side of the machine frame. The frames 83 and 100 may then be replaced. The shaft 60 (Fig. 5) may then be 10 shifted axially to the left to disconnect the clutch 64 from the chain sprocket 65. The sleeve-like hub 97 of the sprocket 96 may then be detached from the shaft 62 and the latter may be disassembled and turned end for end and replaced in its reversed position within the gear housing. The sleeve-like sprocket hub 97 is then attached to the opposite end of the shaft 62 and the clutch 64 may be shifted axially to connect the sprocket 77 thereto for high speed drive in the reversed position of the shaft 62. The gear 67 meshes with the gear 82 of the low speed drive 20 for the sprocket 65 so that the endless cutter chain 27 may then be driven at a relatively low conveying speed. The transverse wedge carrying frame 83 and the guard 99 are then attached to the rearward portion of the tiltable frame 4 at the opposite side of the loop bar with the breaker wedges projecting forwardly through the loop chain 27 which at that time acts as a conveyor chain. When the parts have been transposed the drive chain 95 may be reattached to the drive sprocket 96.

The general mode of operation of the improved loop miner is as follows: The machine may be trammed about the mine under the propulsion of the endless traction treads 18 of the crawler base and the treads may be controlled in a conventional manner to effect steering of the machine. During tramping the combined cutter and conveyor bar and the core breaker wedges may be swung horizontally about the bar pivots by the swing cylinders 44 into a transport position wherein it extends generally lengthwise of the machine thereby to facilitate movement of the machine through the relatively restricted and sharply curved passageways of an underground mine. When the working place is reached, the cutting and conveyor bar may be swung into the substantially right angle position shown in Fig. 10 and the removable and transposable parts may be assembled on the machine with the cutting and conveyor chains 27 and 28 and the breaker wedges connected to their drives. The motors 55 may then be operated to effect drive of the forward cutter chain 27 at a relatively high cutting speed and to effect drive of the rear conveyor chain 28 at a relatively low conveying speed. When the loop bar is properly positioned at the end of the working face the conveyor 7 is connected to its drive and the crawler treads may be operated to propel the machine at a relatively low cutting speed along the face of the mine vein. The front cutter chain, as the machine advances, cuts out a core of mineral of generally rectangular shape (Fig. 6) and as the core is formed the breaker wedges penetrate and dislodge the core. The dislodged mineral is received by the rear conveyor chain 28 and is conveyed laterally along the trough-like guard plates to discharge onto the conveyor 7 by which the dislodged mineral is conveyed forwardly lengthwise of the machine to discharge onto the extensible conveying means 8 (Fig. 10).

If it is desired to adjust the operating height of the loop cutter and conveyor, fluid under pressure may be supplied to the fluid cylinders 35 to move the pistons 36 upwardly thereby to elevate the upper U-frame of the cutter and conveyor bar. In Fig. 6 the bar is shown in its lowermost collapsed position and in Fig. 9 the bar is shown in its uppermost elevated position, and there is sufficient slack in the chains to permit such adjustment. The breaker wedges may penetrate and dislodge the core irrespective of the height of the latter and in any adjusted position of the loop bar. The front cutter chain may cut

out the core while the rear conveyor chain may convey the dislodged mineral laterally onto the conveyor 7. When it is desired to locate the loop cutter and conveyor bar into its substantially right angle position at the opposite side of the machine, as shown in dotted lines in Fig. 10, the rear guard plates and the wedge carrying frame are removed, the drive chain 95 is disconnected and the drive shaft and sprocket parts are dismantled and turned end for end on the gear housing and when the bar is in its reversed substantially right angle position the parts are transposed and reassembled on the machine to permit reverse operation of the machine. Fluid jacks 10 may be operated at will to effect tilting of the frame 4 about its pivot 3 to enable the loop cutter and conveyor chains to follow the contour of an uneven mine floor or rolling bottom in a well known manner.

As a result of this invention an improved crawler mounted loop miner is provided having improved reversible loop cutting and conveying means disposable in substantially right angle positions at either side of the machine to enable operation of the latter in either of opposite directions along the face of a mine vein. By the provision of the improved power operated elevating means operatively associated with the adjustable loop cutting and conveying bar parts the operating height of the bar may be varied to accommodate itself to mine veins of varying heights as desired in an extremely efficient manner. The improved core breaker means is mounted and arranged in an improved manner with respect to the cutting and conveying bar and is effective to dislodge the core of mineral irrespective of the effective operating height of the bar or the size of the core. The improved driving means for the reversible cutting and conveying chains and the core breaker wedges including the detachable and transposable parts render the machine readily reversible in a relatively simple manner. The improved machine is not only relatively flexible and efficient in operation but is also simple and rugged in design, well adapted for its intended purpose. Other advantages of the invention will be clearly apparent to those skilled in the art.

While there is in this application specifically described one form which the invention may assume in practice, it will be understood that this form of the same is shown 45 for purposes of illustration and that the invention may be modified and embodied in various other forms without departing from its spirit or the scope of the appended claims.

What I claim as new and desire to secure by Letters 50 Patent is:

1. In a mining machine, a support, an open-centered core cutter for cutting out a core of mineral from a solid mine vein, transposable means for mounting said core cutter to extend laterally at either side of said support, and core breaker means carried by said mounting means and extending in parallelism with said core cutter at the trailing side thereof for penetrating and dislodging the core in either position of said core cutter, said core breaker means comprising a transposable transverse frame 55 disposable on said mounting means in parallelism with said core cutter rearwardly of the latter in either position of the core cutter, means for transposably mounting said transverse frame on said mounting means at either side of said core cutter, and core breakers carried by 60 said transverse frame and projecting forwardly within said core cutter into engagement with the core for penetrating and dislodging the latter in either position of said core cutter.

2. A mining machine as set forth in claim 1 wherein 70 conveying means is carried by said transposable mounting means for said core cutter and is transposable with said core cutter at either side of said support for conveying away the dislodged mineral, said conveying means disposed intermediate said core cutter and said transverse frame in parallelism therewith in either transposed posi-

tion thereof and extending beneath and movable relative to said core breakers.

3. A mining machine as set forth in claim 2 wherein a guard plate is carried by said transposable transverse frame beneath said core breakers and extends downwardly at the trailing side of said conveying means in either transposed position of said core cutter for confining the dislodged mineral to be conveyed in the path of said conveying means.

4. In a mining machine of the character disclosed, a support movable in either of opposite directions along the face of a mine vein, a loop cutter bar having an open center, mounting means for said bar on said support and adjustable relative to the latter, said bar being disposable laterally of said support at either side of the latter, said bar providing guideways at its opposite sides, endless loop chains guided for orbital circulation along said guideways respectively, and each carrying cutting elements whereby either chain may serve as a cutter chain depending on the direction of movement of said body of said support along the mine face, the cutter chain as said support moves along the mine face cutting out a core of mineral from the solid vein, transposable breaker means attachable to said mounting means and disposable with respect to said bar at either side thereof, said breaker means extending in parallelism with said chains at the trailing side of the rearward chain which then serves as a conveyor chain, said breaker means at either of its transposed positions having breaker elements extending within the open center of said bar to engage and dislodge the core, said chain which acts as a conveyor chain moving the dislodged mineral in a lateral direction in either position of said bar, and means carried by said mounting means for attaching said breaker means thereto in either transposed position of said breaker means.

5. In combination, a support movable in either of opposite directions along the face of a mine vein, core cutting means having an open center and operating to cut a core from a solid mine vein during either direction of movement of said support, means for mounting said core cutter means on said support for transposition into reversed positions relative thereto, core breaker means carried by said mounting means and transposable to positions at opposite sides of said cutter means, said core breaker means located rearwardly of said cutter means during either direction of operation thereof and comprising penetrating and breaker elements extending longitudinally within the open center of said core cutter means for penetrating and breaking the core, means for selectively attaching said core breaker means to said mounting means at either side of said cutting means, said cutter means also having a conveying function, a transposable guard beneath said core breaker elements for confining the dislodged mineral in the path of said cutter means during its conveying function, and means for selectively attaching said guard to said mounting means at either side of said cutter means so that it always trails the latter.

6. In combination, a support movable in either of op-

posite directions along the face of a mine vein, a core cutter for cutting out a core of mineral from the solid mine vein, means for pivotally mounting said cutter on said support to swing horizontally into right angle positions at either side of said support, a detachable core breaker means for penetrating and breaking the core formed by said core cutter and having penetrating and breaker elements extending longitudinally within said core cutter, said core breaker means carried by and swingable with said cutter mounting means and disposable rearwardly of said cutter in either substantially right angle position thereof, and means for attaching said core breaker means to said mounting means selectively at either side of said cutter.

10 7. A combination as set forth in claim 6 wherein said cutter also has a conveying function and a transposable guard is attachable to said mounting means selectively at either side of said cutter in adjacency to and below said penetrating and breaker elements of said core breaker means.

15 8. In a mining machine, a support, an adjustable open-centered core cutting means variable in height for cutting out cores of mineral of different heights from a solid mine vein, means for pivotally mounting said cutting means on said support to swing horizontally relative thereto into operating positions at either side of said support, core breaker means carried by and swingable with said pivotal mounting means and having penetrating and breaker elements extending longitudinally within the open center of said core cutter means for penetrating and dislodging the core from the solid irrespective of the adjusted height of said cutting means, said breaker means being transposable and means for attaching said breaker means to said mounting means in either transposed position thereof, said core cutting means being reversible and said mounting means being swingable to locate said cutting means in cutting positions at either side of said support, and said core breaker means being transposable and having means for selectively mounting the same on said pivotal mounting means at either side of said core cutting means at the trailing side of the latter.
